UNITED STATES PATENT OFFICE.

PETER HUEBSCHWERLEN AND JOHN F. ROMIG, OF ESTEVAN, SASKATCHEWAN, CANADA.

RAILWAY-TIE AND RAIL-JOINT MEANS THEREFOR.

No. 882,319.

Specification of Letters Patent.

Patented March 17, 1908.

Application filed June 25, 1907. Serial No. 380,666.

To all whom it may concern:

Be it known that we, PETER HUEBSCHWERLEN, a subject of the King of Great Britain, and JOHN F. ROMIG, a citizen of the United States, both residing at Estevan, Saskatchewan, Canada, have invented certain new and useful Improvements in Railway-Ties and Rail-Joint Means Therefor, of which the following is a specification.

10 The object of this invention is to provide novel means, particularly designed for use in connection with railroad construction, for securing rails to the ties of the road-bed, bracing the rails at proper intervals, and connecting the meeting-ends of said rails.

The invention involves peculiar attaching means including a special form or construction of ties, the whole being such as to give the requisite rigidity to the structure, admit 20 of quick application or removal of the various parts for purposes of repair, or the like, and embodying various other advantageous features intended to promote the practicality and commercial desirability of the invention.

25 For a full understanding of the invention and the merits thereof, reference is to be had to the following description and accompanying drawing, in which;

Figure 1 is a view taken about on the line 30 1—1 of Fig. 2, looking in the direction of the arrow, and showing the preferred embodiment of the invention. Fig. 2 is a top plan view bringing out more clearly the details of construction and arrangement of the parts of 35 the invention. Fig. 3 is a detail view of the slide-plate fastening member for the angle-bar. Fig. 4 is a detail perspective view of the angle-bar.

Corresponding and like parts are referred 40 to in this description and indicated in the drawings by like reference characters.

Specifically describing the invention, the numeral 1 indicates the railway ties and the numeral 2 the rails supported thereon. The 45 ties 1 may be constructed of any suitable material within the contemplation of the invention and are formed with tapering or wedge-shaped seats 3 in the upper sides thereof, said seats being of dove-tail form in cross section, thus providing overhanging flanges 4 at opposite longitudinal edges thereof. In each seat 3 of the tie 1, a rail is received with its base solid upon the bottom of the said seat and at one side thereof is a recess 5 located adjacent thereto and formed 55 in the body of the tie, extending entirely

across the same. The recesses 5 are provided, one for each seat, and are situated longitudinally of the latter and sufficiently to one side to admit of the rails 2, supported in 60 the seats, having a broad bearing upon the bottom thereof.

The recesses 5 are adapted to receive securing plates 6 therein, the upper sides of these plates being flush with the bottoms of the 65 seats 3 when the parts are in operative position. Angle-bars 7 constituting rail clamping plates are utilized to secure the rails 2 in position on the ties 1, said bars being of special form and being held in place in the 70 seats 3, and bearing against adjacent sides of the rails, by the plates 6 and coacting members. Each rail 2 has one side of its base engaged by an inner flange 4 of each seat, while at the opposite side is arranged 75 the angle-bar 7, the vertical wing of this member bearing against the web of the rail and its horizontal wing being of tapered wedge-like form so that its outer edge engages beneath the outer flange 4 of the seat 80 3. In other words each angle-bar 7 has a wedging coöperation with the seat 3 receiving the same, and is thereby held securely against the adjacent side of the rail 2, bracing the latter and firmly holding the same in 85 place. A fastening member 8 projects upwardly from the plate 6 beneath the angle-bar 7, and passes through a transverse slot 9 in the latter. A nut 10 may be applied to the upper end of the member 8 and securely 90 attaches the angle-bar 7 to the tie and against the rail 2 with which it is coöperating.

When the member 7 is used as a brace and for attaching the rail to the tie 1, as shown at the right in Fig. 2, said member is driven 95 into position in the seat 3, simultaneously with the plate 6, the fastening 8 having previously been engaged into the slot 9. The slot 9 is necessary to permit of the lateral movement incidental to the wedging of the 100 angle-bar 7 against the rail 2, in the above operation. The security of the fastening means for the bars 7 will be obvious from the above.

As shown most clearly in Fig. 1, and at the 105 left in Fig. 2, the angle-bars 7 may be employed in connection with the fish-plates 11, in order to secure the rails 2 together at the meeting ends. Under these conditions the members 7 and 11 are connected by the usual 110 bolts 12 or similar fastenings, passing through the rails 2, the angle-bars having elongated

openings to receive the bolts 12. Expansion and contraction of the rails, caused by varying weather conditions, is thus fully accommodated for in the actual embodiment of this invention. From the foregoing it will be understood that at points between the meeting and connected ends of the rails, the latter are rigidly braced and secured to the ties 1 by the angle-bars 7, the fish-plates 11 and fastenings 12 being used in connecting rail ends, as before described.

Our invention is not to be restricted to the exact form of the parts as set forth and illustrated, as these may be modified in accordance with the broad spirit of the invention as defined in the claims forming a part of this specification.

It will be apparent that the plates 6 and the horizontal wings of the angle-bars 7 have a firm interlocking connection with the tie, said plates 6 forming supporting means adapted to move with the angle-bars and carrying the fastening members by which the latter are firmly connected with the tie. Furthermore, the outer flange 4, against which the outer edge of the angle-bar or clamping member 7 engages, forms a rigid bearing for the member 7 as it is moved transversely of the tie to the desired adjustment, and the fastening means including the member 8 is not subject to any strain whatever

in the movement of the angle-bar and is not liable to be broken.

Having thus described the invention, what is claimed as new is:

1. In combination, a railway tie, a rail supported thereon, means securing the rail to the tie including a transversely movable angle-bar engaging the rail and having wedging coöperation with the tie, a transverse slidably movable plate interlocking with the tie, and a pin and slot connection between said plate and the angle-bar and located at a right angle to the line of movement of the angle bar.

2. In combination, a tie having a transverse dove-tail shaped seat therein forming edge flanges, a rail supported in said seat and engaged by one of said flanges, a transversely movable wedge-shaped angle-bar engaging the rail and bearing against the tie, a plate interlocking with the tie at the bottom of the recess, and a fastening projecting from said plate and entering a slot in the angle-bar.

In testimony whereof we affix our signatures in presence of two witnesses.

PETER HUEBSCHWERLEN.
JOHN F. ROMIG.
